United States Patent Office

Des. 189,335
Patented Nov. 22, 1960

189,335

FAUCET

James D. Whetstone, Parkman, Ohio, assignor to Multi-Meter Corporation, Toledo, Ohio, a corporation of Ohio

Filed Feb. 4, 1959, Ser. No. 54,456

Term of patent 14 years

(Cl. D91—3)

Fig. 1 is a view in perspective of a faucet showing my new design;

Fig. 2 is a top plan view thereof;

Fig. 3 is a front view in elevation of the faucet;

Fig. 4 is a rear view in elevation of the faucet; and

Fig. 5 is a bottom plan view of the faucet.

I claim:

The ornamental design for a faucet, substantially as shown.
